(57) **CLAIM**

The ornamental design for a mobile phone protective case, as shown and described.

DESCRIPTION

FIG. 1 is a front view of a mobile phone protective case of the present invention when the case is in a closed configuration.

FIG. 2 is a rear view of the mobile phone protective case shown in FIG. 1.

FIG. 3 is a left view of the mobile phone protective case shown in FIG. 1.

FIG. 4 is a right view of the mobile phone protective case shown in FIG. 1.

FIG. 5 is a top view of the mobile phone protective case shown in FIG. 1.

FIG. 6 is a bottom view of the mobile phone protective case shown in FIG. 1.

FIG. 7 is a view of the interior of the mobile phone protective case of the present invention when the case is in an open, fully expanded configuration.

FIG. 8 is another front view of the mobile phone protective case of the present invention when a flap of the front cover of the case is in an open configuration.

FIG. 9 is a perspective view of the mobile phone protective case of the present invention when the case is in a deployed, self-standing configuration for supporting a mobile phone to be viewed at a tilted angle.

FIG. 10 is another perspective view of the mobile phone protective case of the present invention as shown in FIG. 9.

FIG. 11 is a front view of the mobile phone protective case as shown in FIG. 9.

FIG. 12 is a rear view of the mobile phone protective case as shown in FIG. 9.

FIG. 13 is a left view of the mobile phone protective case as shown in FIG. 9.

FIG. 14 is a right view of the mobile phone protective case as shown in FIG. 9.

FIG. 15 is a top view of the mobile phone protective case as shown in FIG. 9; and,

FIG. 16 is a bottom view of the mobile phone protective case as shown in FIG. 9.

The broken line showing of certain portions of the mobile phone protective case is included for the purpose of illustration only and forms no part of the claimed design.

1 Claim, 14 Drawing Sheets
